UNITED STATES PATENT OFFICE.

CHARLES D. STONE, OF BROOKLYN, NEW YORK.

COMBINED STAIR-CARPET FASTENER AND STAIR-ROD SECURER.

SPECIFICATION forming part of Letters Patent No. 252,850, dated January 24, 1882.

Application filed November 25, 1881. (No model.)

To all whom it may concern:

Be it known that I, CHARLES D. STONE, a citizen of the United States, residing at Brooklyn, in the county of Kings and State of New York, have invented certain new and useful Improvements in Stair-Carpet Fasteners, of which the following is a specification, reference being had therein to the accompanying drawings, in which—

10 Figure 1 is a view showing my stair-carpet fastener and stair-rod fixture. Fig. 2 shows it as applied for holding a stair-rod. Fig. 3 is a detailed view thereof, showing it capable of adjustment to carpets or stairs of different widths; and Fig. 4 is a modification of my invention.

15 In this class of devices accommodation to stairs or carpets of different widths, and capability of putting down stair-carpets without rods, while permitting of their use, are very desirable, lessening expense and labor in carpeting the stairs. To effect these is the object of my invention, which consists of hook-shaped brackets, either with or without eyes, to receive 20 or hold stair-rods, substantially as hereinafter more fully set forth.

25 In carrying out my invention, I employ a bracket, A, formed of metal, or a wire doubled together, having screw-holes a a at one end, and turned over and brought back to a point 30 to form a sufficiently lengthened or sized hook to retain the edge of the carpet inserted thereunder. To permit of the use of stair rods, if desired, each bracket is provided with an eye 35 or socket, A', to receive the rod. These brack-

ets may be placed at any distance apart to accommodate carpets or stairs of different widths, and by their construction (being open at their inner ends) they admit the ready insertion of the edges of the carpet thereunder, thereby 40 facilitating and lessening the labor of putting down the carpet.

It will be understood that I do not limit myself to the construction of the brackets, as described, in the formation therewith of the rod-eyes, as they may be made as shown in Fig. 4.

Having thus fully described my invention, I claim and desire to secure by Letters Patent—

1. The stair-carpet fastener consisting of bracket A, formed of a wire doubled together 50 and having screw-holes a a, thence turned over and brought back to overhang the shank, substantially as set forth.

2. In a stair-carpet fastener and stair-rod fixture, an arm which extends inwardly to overhang the carpet, and thence outwardly, forming a socket or eye to receive a stair-rod, as and for the purpose set forth. 55

3. The stair-carpet fastener and stair-rod fixture consisting of bracket A, formed of a wire 60 doubled together and having screw-holes a a, thence turned over and brought back to overhang the shank, and terminating in an eye, A', substantially as set forth.

In testimony whereof I affix my signature 65 in presence of two witnesses.

CHARLES D. STONE.
